UNITED STATES PATENT OFFICE.

THOMAS MOLLOY, OF ROXBURY, MASSACHUSETTS.

TOBACCO PIPE.

Application filed June 19, 1922. Serial No. 569,366.

To all whom it may concern:

Be it known that I, THOMAS MOLLOY, a citizen of the United States, and resident of Roxbury, county of Suffolk, State of Massachusetts, have invented an Improvement in Tobacco Pipes, of which the following description, in connection with the accompanying drawing, is a specification, like characters on the drawing representing like parts.

10 This invention relates to tobacco pipes and has for its general object to provide a novel pipe construction by which the moisture and nicotine will be trapped before it reaches the end of the pipe stem so that the 15 smoker will always enjoy a dry smoke.

In order to give an understanding of my invention I have illustrated in the drawings a selected embodiment thereof which will now be described after which the novel features 20 will be pointed out in the appended claims.

In the drawings, Fig. 1 is a vertical sectional view through a pipe embodying my invention.

25 Fig. 2 is a top plan view.

The pipe shown in the drawing comprises the usual bowl 1 and stem 2. This stem is made in sections, one section 3 being integral with the bowl 1 and the other section 4 constituting 30 the mouth piece and being detachable. The two sections are connected together by a connecting member 5 which is provided with two bosses 6 that enter recesses formed in the ends of the stem sections 3 and 4. The 35 stem sections 3 and 4 are provided with the usual duct 7 and the connecting section 5 is also provided with a duct 8 extending therethrough which is situated in alignment with the duct 7.

40 In order to provide a construction which will trap any moisture or nicotine that tends to be drawn through the smoke duct I propose to form the stem with two chambers communicating with the duct and which are connected by a by-pass situated above the pipe stem. The chambers have absorbent material therein and when in use the smoke will be drawn from one chamber to the other around through the by-pass and any moisture or nicotine will become trapped in the 45 chambers and will be absorbed by the absorbent material. These two chambers are shown at 9 and 10 and they are positioned either side of the connecting member 5. In 50 fact the chambers form continuations of the

recesses in the stem sections into which the bosses 6 of the connecting member are received. The by-pass connecting the chambers is indicated at 11 and is formed in a U-shaped tubular member having its ends 60 received in apertures formed in the stem sections 3 and 4. This by-pass is preferably formed with a chamber 12 which may have absorbent material 13 situated therein. Each of the chambers 9 and 10 also has absorbent 65 material therein as shown at 15 and such absorbent material is forced firmly into the duct 8 so that the smoke cannot be readily drawn through said duct. On the other hand the absorbent material 13 in the chamber 12 will be loosely placed therein so that the smoke may be easily drawn therethrough.

When the pipe is in use the smoke from the bowl will be drawn through the stem 75 section 3 into the chamber 9 and thence around through the by-pass 11 into the chamber 10 and thence through the stem section 4. The smoke will take this course because the density of the absorbent material 80 in the duct 8 is much greater than that in the chamber 12, and the by-pass presents much less resistance to the passage of the smoke than the duct 8 itself. If any moisture or nicotine tends to enter the duct 7 it 85 will become trapped in the chamber 9, because of the fact that the by-pass 11 enters the top of the chamber and the smoke will readily pass upwardly into the by-pass while moisture and nicotine which is heavier will 90 accumulate in the bottom of the chamber 9 and will be absorbed by the absorbent material. If there should be any condensation at the delivery end of the by-pass 95 the moisture will collect in the chamber 10 and will be absorbed by the absorbent material therein.

The by-pass pipe is removable from the pipe stem, the ends of said by-pass pipe being freely withdrawable from the apertures 100 in the pipe stem. This by-pass pipe is also shown as made in two sections 16 and 17 which are detachable from each other at the chamber 12 thereby providing for renewing the absorbent material 13.

105 The by-pass pipe is shown as having an enlarged central portion 18 within which the chamber 12 is formed and the joint between the two sections 16 and 17 is located at this chamber. Each section has an en- 110

larged end and one section has a recess into which a lip 19 on the other section is received.

Whenever it is desired to renew the absorbent material 15 it is simply necessary to first remove the by-pass pipe 11 and then to separate the main sections 3 and 4 and remove the connecting section 5. When this is done the absorbent material 15 can be readily removed from the connecting section and fresh absorbent material put in place after which the parts may be assembled.

My improved pipe is sanitary and it also will operate to prevent the passage of any nicotine or moisture through the stem section 4.

I claim.

1. A tobacco pipe provided with the usual bowl and stem, the latter having a duct leading therethrough and formed with two chambers with which the duct communicates, a by-pass duct leading from one chamber to the other and situated above the chambers and absorbent material in the portion of the first-named duct that connects the chambers.

2. A pipe having a bowl and stem made in two sections, a connecting member uniting said sections, said stem and connecting member having a duct extending there-

through and said stem having two chambers therein one on either side of the connecting member, and a by-pass duct leading from one chamber to the other, each chamber having absorbent material therein. 35

3. A pipe having a bowl and stem made in two sections, a connecting member uniting said sections, said stem and connecting member having a duct therethrough and 40 said stem having two chambers therein situated one on either side of the connecting member, a by-pass duct connecting said sections and provided with a chamber, and absorbent material in each of the chambers 45 of the stem and also in the chamber of the by-pass.

4. A pipe having a bowl and stem made in two sections, a connecting member uniting said sections, there being a duct extending through the stem sections and connecting member and two chambers in the stem one on either side of the connecting member, a by-pass conduit connecting said chambers and made in separable sections, and absorbent material in the chambers and filling 50 the ends of the duct in the connecting member. 55

In testimony whereof, I have signed my name to this specification.

THOMAS MOLLOY.
